UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

DRAFT RIGGING.

Application filed July 2, 1923. Serial No. 648,867.

This invention relates to improvements in railway draft riggings.

An object of this invention is to provide a strong and flexible means of attaching a draft gear to the draft sills of a car, and one which may be easily applied and removed.

Another object of the invention is to provide a draft rigging wherein a single casting is employed, detachably secured between the draft sills, to which are transmitted all the buffing and pulling shocks.

A still further and more specific object of the invention, is to provide a draft rigging, wherein is employed, in combination with a shock absorbing mechanism, a two part yoke, a central strap and a stop block directly co-acting with the strap and removably attached to a holding means fixed to the draft sills.

In the drawings forming a part of this specification, Figure 1 is a longitudinal, horizontal, sectional view of a draft rigging showing my improvements in connection therewith. Fig. 2 is a longitudinal, vertical, sectional view corresponding substantially to the line 2—2 of Fig. 1. Figures 3 and 4 are vertical, transverse, sectional views corresponding substantially to the lines 3—3 and 4—4 respectively of Fig. 1. And Fig. 5 is a detail perspective view of a filler block used in connection with my improved draft rigging.

In said drawings, 10—10 denote channel shaped center or draft sills, to the outer ends of which is secured a transversely extending striking casting 11. Disposed between the center sills 10 and rigidly secured thereto, preferably by rivets, is a hollow stop casting A, preferably made in one piece.

The stop casting A is provided with spaced side walls 12—12, a top wall 13, a bottom wall 14, a vertically disposed transversely extending central wall 15 and a plurality of horizontally disposed, spaced, transverse strengthening webs 16. As clearly shown in Fig. 2, the front end of the bottom wall 14 terminates flush with the central wall 15, thereby providing a bottom opening 17 between the front portions of the side walls 12. Forwardly of the wall 15, the top wall 13 is arched as indicated at 18 in Figures 2 and 4, for a purpose herein-after described. The side walls 12 extend forwardly beyond the outer end of the wall 15 an appreciable distance and are provided

with inwardly projecting, narrow, marginal flanges 19 along the top, bottom and front edges thereof. The side walls 12 between the front ends thereof and the wall 15 are provided with oppositely disposed, inwardly projecting, vertical hollow abutments 20 equally spaced from the wall 15, thereby providing a pair of vertically disposed, interior channels 21 at the opposite sides of the stop casting A.

The filler block B is detachably connected to the stop casting A. The filler block B as most clearly shown in Figures 1, 2 and 5, is in the form of a hollow casting, provided with laterally projecting, vertically disposed, hollow flanges 22 at the rear end thereof adapted to engage within the channels 21, a flat front wall 23 adapted to form an abutment for the shock absorbing mechanism proper C, and a rear wall 24 adapted to abut the front side of the wall 15 of the stop casting. When the parts are in assembled relation, the front and rear faces of the flanges 22 are adapted to engage the abutments 20 and the wall 15 respectively, with the rear wall 24 in abutment with the wall 15, thereby holding the filler block B rigidly interlocked with the stop casting A. The upper and lower faces of the filler block are recessed as indicated at 25 in Figures 2 and 5, for a purpose hereinafter described, providing front and rear shoulders 26 and 27, respectively.

The shock absorbing mechanism proper C, is of that type wherein is employed a casting having a friction shell or cylinder 28 and integral spring casing 29, the latter having therewithin a spring resistance 30 and the shell having mounted therewithin a plurality of friction shoes 31 and a wedge 32. The wedge 32 engages a flanged coupler guide-plate and filler block 33 employed on the inner side of a central strap D, with which the shock absorbing mechanism is operatively associated, the filler block also acting as a front follower.

The shock absorbing mechanism C is operatively connected to a draw bar 34 by means of a two part yoke E—E, the latter being provided with elongated slots to receive a coupler key 35, the ends of the latter also sliding in elongated slots 36 in reinforcing guide plates 37 rigidly secured to the center sills. As clearly shown in Figures 1 and 2, the draw bar extends through

the striking casting 11 and is supported by a carry iron 47 secured to the lower side of said casting.

Each of the members E of the two part yoke, which are preferably of like construction, is provided with a rectangular recess 38 near its rear end and in which is adapted to be received one side of the substantially rectangular spring casing 29. Each member 10 E has its forward portion tapered as indicated at 39 and provided with a slot 48, as hereinbefore described. The yoke members fit over the spring casing 29, and clear the cylinder or shell 28. The members E are 15 guided and supported in operative position by the casing 29 and a detachable saddle plate 40 supports the central strap D and the shock absorbing mechanism therewithin, a flanged spacing and wear plate 41 being 20 interposed between the saddle plate and the central strap D, and held in position by the downwardly projecting flanges thereof. The front end portions of the members E are 25 adapted to have sliding engagement between the guide plates 37 and the complex guide-plate 33, and the rear end portions thereof are disposed between the inner sides of the front ends of the walls 12 of the casting A and the front end portion of the block B, the 30 outer side faces thereof having sliding engagement with the inner edges of the flanges 19.

The central strap D is in the form of a yoke, having upper and lower parallel arms 35 42 embracing the shock absorbing mechanism and straddling the casing 29, the arms 42 being connected at their front ends by a vertically extending portion 43 adapted to co-act with and abut the rear face of the 40 draw-bar 34.

At the rear ends, the arms 42 are provided with inwardly extending projections 44, thereby providing transverse shoulders 45, the projections being formed by doubling 45 over the ends of the arms, as clearly shown in Fig. 2, or in any other suitable manner. The projections 44 are slidably received within the recesses 25 of the block B and the shoulders 45 are adapted to co-act with the 50 shoulders 26 to limit the forward movement of the central strap D. A band 46 of rectangular outline surrounds and engages the rear end portions of the arms 42 preventing separation of the same and holding the parts 55 in assembled relation; the recessed portion 18 of the top wall accommodating the upper part of the band and upper arm 42 of the strap D.

The entire mechanism is readily removable 60 from between the sills, it being merely necessary to detach the saddle plate and remove the key 35 to lower the same, the flanges 22 of the filler block sliding downwardly in the guide channels of the stop casting, the 65 opening 17 in the bottom of the latter per-

mitting withdrawal of the filler block. In placing the gear in operative position between the draft sills, the assembled mechanism is inserted between the same from the bottom, the filler block being passed through 70 the opening 17 and the flanges 22 engaged within the guide channels 21.

All the parts are readily removable and by employing the two part yoke, I am enabled to use a key connection with the coupler 75 and at the same time the yoke members E—E are independently longitudinally movable to thereby accommodate themselves to the movements of the coupler when the latter is swung radially as occurs when the cars are 80 traveling over curved tracks.

The operation is as follows. In buff the draw-bar presses against the strap D moving the latter rearwardly thus actuating the friction mechanism, since the combined shell and 85 casing 28—29 is prevented from rearward movement by engagement with the front face 23 of the filler block B, held against rearward movement by abutting the wall 15 of the fixed stop casting A. Rearward movement of the strap D relatively to the filler block B is permitted by the ends of the strap sliding in the recesses 25 of the block. 90

Upon draft, the strap D is prevented from movement by the shoulders 45 on the arms 42 95 engaging with the shoulders 26 of the filler block B, the block B in turn being held in fixed position by the flanges 22 thereof engaging the abutments 20 on the stop casting, so that as the draw-bar moves forwardly 100 carrying the two part yoke E—E therewith, the friction shell and casing 28—29 slides forwardly relatively to the wedge and shoes of the friction mechanism, thereby absorbing the shock as will be understood. 105

I have herein shown and described what I now consider the preferred manner of carrying out the invention, but the same is merely illustrative, and I contemplate all changes and modifications that come within 110 the scope of the claims appended hereto.

I claim:

1. In a draft rigging, the combination with draft sills; of a stop casting secured to said sills; an abutment member detachably secured to said casting and held against movement longitudinally of the sills; a shock absorbing mechanism adapted to abut said member; a strap enclosing said mechanism, said strap having a pair of arms slidably engaged with said member; co-acting means on said member and arms for limiting the sliding movement of the latter; a draw-bar co-acting with said strap; and a yoke connecting said mechanism with said draw-bar. 115

2. In a draft mechanism, the combination with draft sills; of a stop casting secured thereto; an abutment block; means for detachably connecting said block to said cast- 120 125

- ing and preventing movement of said block in a longitudinal direction, including inter-engaging abutments on the abutment block and said casting; a shock absorbing mechanism adapted to abut said block; a strap enclosing said mechanism, said strap including a pair of arms having the rear ends thereof engaging said block for limiting the movement of said strap; a draw-bar co-acting with said strap; and a two part yoke connecting said mechanism with the draw-bar.
3. In a draft rigging, the combination with draft sills; of a stop casting secured thereto; an abutment block having longitudinally extending guideways provided with stop shoulders; means for detachably connecting said block to said casting and preventing movement of the block in a longitudinal direction; a shock absorbing mechanism adapted to abut said block; a strap enclosing said mechanism, said strap having lugs working in said guideways and co-acting with said stop shoulders to limit the forward movement of said strap; a drawbar coacting with said strap; and means connecting said shock absorbing mechanism with said drawbar.
4. In a draft rigging, the combination with draft sills; of a stop casting secured thereto; an abutment block having stop shoulders thereon; means for detachably connecting said block to said casting and preventing movement of said block in a longitudinal direction; a shock absorbing mechanism adapted to abut said block; a strap enclosing said mechanism, said strap including a pair of arms having shoulders co-acting with the shoulders of said block to limit the forward movement of the strap; a draw-bar co-acting with said strap; and a two part yoke connecting said mechanism with the draw-bar.
5. In a draft rigging for railway cars, having draft sills, the combination with a member having means detachably inter-engaging with cooperating means on said sills and located at the inner end of the shock absorbing mechanism, said member being removable vertically downwardly from between the sills without destructive effect; of a shock absorbing mechanism proper adapted to transmit the buffing shocks therefrom to the front end of said member; yoke-acting means adapted to be attached to a draw-bar and co-operable with said shock absorbing mechanism to compress the latter under draft; and means movably connected to said member and extended forwardly therefrom and across the front of the shock absorbing mechanism and to which the pull is transmitted under a draft action, whereby said member is adapted to receive both the buffing and draft shocks.
6. In a draft rigging, the combination with draft sills; of stop means detachably connected to the draft sills; a shock absorbing mechanism adapted to abut said means; a strap enclosing said mechanism, said strap having abutment means thereon engaging said stop means for limiting the forward movement of the strap; a draw-bar co-acting with said strap; a follower within said strap and co-acting with said mechanism, said follower having forwardly extending flanges projecting beyond said strap and functioning as guides and centering means for the draw-bar; and yoke means connecting said mechanism with the draw bar.
7. In a draft rigging, the combination with draft sills; of a stop casting secured to the draft sills; yoke acting means adapted to be attached to a draw-bar; a shock absorbing mechanism disposed within the yoke; and means connected to said stop casting for sustaining both buffing and draft shocks, including an abutment element detachably engaged with said stop casting adapted to directly co-act with the rear end of the shock absorbing mechanism to receive the buffing shocks therefrom and slidably abutment means adapted to engage said element and co-acting with the front end of the shock absorbing mechanism to receive the pull under draft action.
8. In a draft rigging, the combination with draft sills; of a stop casting secured to the draft sills; yoke-acting means adapted to be attached to a draw-bar; a shock absorbing mechanism disposed within the yoke acting means; means detachably connected to said stop casting for sustaining both buffing and draft shocks, including abutment means adapted to co-act with the rear end of the shock absorbing mechanism to receive the buffing shocks therefrom and abutment means co-acting with the front end of the shock absorbing mechanism to receive the pull under draft action; and means secured to the forward portion of said latter abutment means for maintaining rear end of drawbar in a relatively longitudinally central position.
- In witness that I claim the foregoing I have hereunto subscribed my name this 27th day of June 1923.

STACY B. HASELTINE,
